CLAIM

The ornamental design for a cat-shaped mousetrap, as shown and described.

DESCRIPTION

FIG. 1 is a perspective of the first embodiment of my cat-shaped mousetrap showing my new design;

FIG. 2 is a left side elevation view thereof;

FIG. 3 is right side elevation view thereof;

FIG. 4 is a front elevation view thereof; and

FIG. 5 is a rear elevation view thereof.

FIG. 6 is a top elevation view thereof;

FIG. 7 is a perspective of a second embodiment of my cat-shaped mousetrap showing my new design;

FIG. 8 is a left side elevation view thereof;

FIG. 9 is right side elevation view thereof;

FIG. 10 is a front elevation view thereof; and

FIG. 11 is a rear elevation view thereof.

FIG. 12 is a top elevation view thereof with the tail offset for clarity of the disclosure;

FIG. 13 is a perspective of a third embodiment of my cat-shaped mousetrap showing my new design;

FIG. 14 is a left side elevation view thereof;

FIG. 15 is right side elevation view thereof;

FIG. 16 is a front elevation view thereof; and

FIG. 17 is a rear elevation view thereof; and,

FIG. 18 is a top elevation view thereof with the tail offset for clarity of the disclosure.

The broken lines in the drawings depict portions of the cat-shaped mousetrap that form no part of the claim. The additional broken lines in FIGS. 12 and 18 show the direction of the offset and form no part of the claim.

1 Claim, 18 Drawing Sheets
